GRAFTON W. APPLER, OF LYONS, NEW YORK.

REFILLABLE FUSE-CARTRIDGE.

1,093,164.

Specification of Letters Patent. Patented Apr. 14, 1914.

Application filed May 6, 1913. Serial No. 765,789.

To all whom it may concern:

Be it known that I, GRAFTON W. APPLER, of Lyons, in the county of Wayne, in the State of New York, have invented new and useful Improvements in Refillable Fuse-Cartridges, of which the following, taken in connection with the accompanying drawings, is a full, clear, and exact description.

This invention relates to certain improvements in refillable fuse cartridges of the class set forth in my Patent No. 1,052,202, issued February 4, 1913, except that the primary object of my present invention is to provide for the use of a multiple fuse or fuses either laminated or arranged in such close juxtaposition as to dissipate to an appreciable extent the force of an explosion due to the thermal disintegration.

I have found that, in the use of the ordinary single fuse cartridge in connection with light and power distributing systems and other comparatively high voltage circuits, the force of explosion resulting from sudden thermal disintegration of the fuse is frequently sufficient to disintegrate or impair the cartridge beyond further use, thereby negativing the advantages of a refillable cartridge by necessitating its replacement by a new one. I have also discovered that when a fuse of the desired current-carrying capacity is made up of a multiplicity of parts either laminated or in multiple, the force of explosion incidental to the disintegration of any one of the parts by heat is materially reduced or dissipated through the entire series of fuses. This is due to the fact that the fuse units disintegrate in succession, which although rapid is sufficiently retarded or prolonged to cause the dissipation of such force and thereby reduces the liability of injuring the cartridge.

The primary object, therefore, is to not only provide a refillable cartridge with a multiple fuse or a plurality of fuses connected in multiple, but also to provide simple means for replacing and securing these fuses in operative position within the cartridge.

Other objects and uses will be brought out in the following description.

In the drawings:—Figure 1 is a longitudinal sectional view of a refillable cartridge having knife contacts and a multiplicity of fuses theréin. Fig. 2 is a longitudinal sectional view through one end of the same cartridge taken at right angles to that shown in Fig. 1. Fig. 3 is a transverse sectional

view through one end of the same cartridge showing more particularly the fastening means for one end of the fuses. Figs. 4, 5 and 6 are perspective views respectively of one of the end caps, the adjacent end of the ferrule and the corresponding end of the insulating tube. Figs. 7 and 8 are longitudinal sectional views of one end of a modified form of cartridge taken at right angles to each other, omitting the knife contacts and showing peripheral contact caps.

This cartridge comprises a tubular shell —1— of vulcanized fiber or equivalent insulating material of suitable length having its ends equipped with suitable ferrules —2— of brass or equivalent metal for receiving and supporting end caps —3— also of brass or similar metal.

The ferrules —2— are fitted tightly over and upon the corresponding ends of the insulating tube —1— and are held in place by crimping their inner ends —4— inwardly into corresponding grooves in the tube —1—, thereby holding the ferrules against relative endwise movement or displacement.

The caps —3— are fitted with a snug sliding fit over and upon the ferrules —4— and are frictionally held in operative position by spring tongues —5— on their inner ends, said tongues being preferably provided with indentations —6— projecting inwardly and adapted to enter corresponding depressions —7— in the periphery of the ferrule for additionally holding the caps on the ferrules by friction and, at the same time, permitting said caps to be removed by hand when necessary in placing or replacing the fuses in operative position.

A plurality of fuses —a— are arranged within and lengthwise of the tube —1— and are connected in multiple to the inner ends of suitable knife contact blades —8— which are also inserted within the opposite ends of the tube, as shown more clearly in Figs. 1, 2 and 3, the ends of the fuses being preferably hook-shape and secured to their respective knife contacts by clamping devices —9— so as to establish electrical connection between the fuses and contacts. These fuses may be made of ordinary round or flat fuse wire, but are preferably flat and laminated to further reduce the force of explosion by dissipation and distribution from one lamina to another.

The knife blades —8— preferably consist of separate flat copper bars rectangu-

lar in plan and of substantially the same width as the external diameter of the tube, which latter is provided with diametrically opposite lengthwise slots —10— extending inwardly from the ends thereof and of substantially the same circumferential width as the thickness of the knife blades for receiving the inner ends of said blades and thereby holding them against relative rotation on the ends of the tube, the slots and, therefore, the blades being disposed in the same diametric plane so that the knife blades are supported centrally on the ends of the tubes and in the same flat plane with their edges substantially coincident with the periphery of the adjacent portions of the tube.

The ferrules —2— which, as previously stated, are fitted upon the ends of the tube and, as shown more clearly in Figs. 2 and 3, surround the inner ends or edges of the knife blade —8— and are firmly secured thereto by indenting portions of the periphery of the ferrule into corresponding depressions in the adjacent edges of the blades, thereby firmly holding the blades against relative endwise movement although it is evident that any other suitable fastening means may be employed.

As previously stated, the caps —3— are fitted over and upon the ferrules —2— and frictionally held in operative position by the tongues —5— and depressions —6—, the outer ends of said caps being closed by end walls as —11— having diametrical slots —12— of substantially the same size and form as the cross sectional area of the knife blades —8— which extend outwardly through said slots a sufficient distance to contact with the spring terminals (not shown) of any circuit in which the fuse cartridge is adapted to be connected.

The fuse clamps —9— are preferably located near the outer ends of the tube and in close proximity to the outer ends of the caps —3— and in order that they may be accessible for manipulation by a screw driver or equivalent tool when the caps —3— are removed, as for instance in removing disintegrated fuses and replacing them with new ones, the outer ends of the tube —1— and ferrules —2— are provided with diametrically opposite recesses —12'— extending inwardly from their end faces and alined diametrically with the opposite ends of their corresponding clamps —9—. These clamps are passed through apertures —13— in the knife blades —8— just inside of the outer ends of the caps —3— and each preferably consists of an internally threaded bushing —14— and a screw —15—, the bushings —14— and screws —15— being provided with slotted heads at opposite sides of their corresponding knife blades —8— so as to secure the ends of the fuses —a— to

opposite sides of said blades in the manner shown more clearly in Fig. 1.

In Figs. 7 and 8, I have shown a refillable fuse cartridge similar to that shown in Figs. 1, 2 and 3 except that it is adapted for peripheral contact and for this purpose is provided with a relatively short fuse supporting blade —8'— terminating at the end of the tube —1— and covered by a contact cap —3'— which is screwed or otherwise secured upon the periphery of an externally threaded ferrule —2'—, said ferrule being in close electrical connection with the blade —8'— by reason of its contact with the edges thereof in the manner shown in Fig. 2 so that when the caps —3'— are placed in operative position upon the ferrules, close electrical connection is established between the caps and fuses, it being understood that the outer end walls of the ferrules —3'— are imperforated or unprovided with slots —12— so as to completely close the adjacent open ends of the tube.

In Fig. 3, I have shown the usual filling of any suitable powdered or common insulating substance, such as powdered chalk or similar material which will resist as far as possible attraction or attention.

What I claim is:

1. A fuse cartridge comprising an insulating tube, flat conductor blades secured diametrically in the ends of the tubes in the same flat plane, a fuse, and separate devices on said blades for clamping the ends of the fuse thereto, said insulating tube having an opening through the periphery thereof alined with the fuse-clamping devices for the reception of a tool by which the clamping device may be operated.

2. A refillable fuse cartridge comprising an insulating tube, conductor blades secured diametrically within the tube in the same flat plane, a fuse, separate clamping devices for securing the ends of the fuse to the blades, and metal ferrules secured to the ends of the tube and electrically connected to their corresponding blades, said ferrules being provided with radial openings alined with the adjacent clamping device.

3. A refillable fuse cartridge comprising an insulating tube, conductor blades secured diametrically within the tube in the same flat plane, a fuse, separate clamping devices for securing the ends of the fuse to the blades, and metal ferrules secured to the ends of the tube and electrically connected to their corresponding blades, said ferrules being provided with radial openings alined with the adjacent clamping device, and metal caps closing the open ends of the tube.

4. A refillable fuse cartridge comprising an insulating tube, flat conducting plates secured diametrically in opposite ends of the tube, a plurality of fuses secured to opposite sides of said plates, separate clamping

devices for the ends of the fuse, ferrules secured to the ends of the tube in electrical contact with the adjacent plates, and metal caps slidably fitted upon the ferrules and closing the open ends of the tube.

5. A refillable fuse cartridge comprising an insulating tube having lengthwise slots in its opposite ends, conductor blades projecting into said slots to hold them against turning, and a fuse connecting the blades.

6. A refillable fuse cartridge comprising an insulating tube having diametrical slots in its opposite ends, conductor blades in the ends of said tube and having their edges seated in the adjacent slots, a fuse connecting said blades, and ferrules inclosing the slotted ends of the tube and electrically connected to the blades through the slots.

7. A refillable fuse cartridge comprising an insulating tube having slotted ends, conductor blades seated in the slots in said ends

to hold them against turning, metal ferrules surrounding the slotted ends of the tubes and contacting with the edges of the blades, and fuses having their ends attached to opposite faces of adjacent blades.

8. A refillable fuse cartridge comprising an insulating tube, conductor blades secured against turning in opposite ends of the tube and provided with screw holes, separate fuses extending along opposite faces of the blades, and fuse clamps composed of screw members screwing one into the other through the screw-holes and engaging the adjacent ends of the fuses.

In witness whereof I have hereunto set my hand this 22nd day of April, 1913.

GRAFTON W. APPLER.
